UNITED STATES PATENT OFFICE.

WALTER N. FANNING, OF VALLEJO, CALIFORNIA.

RADIO RECEIVING SYSTEM.

Application filed January 23, 1922. Serial No. 531,121.

My invention relates to a system for receiving radio telegraphy signals and more particularly for relaying received signals to a distant point where it may be recorded or again transmitted, as desired. A relay to transmit the received telegraphic signals must have sufficient strength to operate a mechanical device at a fairly rapid rate, comparable with the rate of signaling. In 10 telegraph systems receiving radio signals, these signals as received are entirely unsuitable for the operation of an electro-mechanical relay. Such relays are operated by an electric current which usually produces 15 a magnetomotive force sufficient to attract an armature when a signal is received. Relays of this type may be made to operate upon a comparatively small variation of the current flowing through its windings, 20 for example, the normal current flow when no signal is received may be 20 milli-amperes, which would be insufficient to attract the armature, while the current flow when a signal is received may have, say, an effective 25 value of 30 milliamperes, although pulsatory, sufficient to attract the armature. Upon a reduction of the current to the normal value of 20 milliamperes, the armature would be released. One of the objects of my 30 invention is, therefore, to make it possible to operate a relay in the manner outlined, in a radio receiving system.

In one form of my invention which I shall describe in detail hereinafter, the relay circuits are so arranged that energy is obtained both from the compensating wave and the telegraphic wave to operate the mechanical device. It is therefore possible to obtain 35 much stronger and more positive signals with the same signaling power.

My invention may also be used for the elimination of static or other interferences. These interferences may, for example, be 40 due to the use of a spark set for transmission since it is well known that such a set transmits, besides its own frequency, a great many other frequencies which tend to confuse the signals.

My invention possesses other advantageous 45 features, some of which, with the foregoing, will be set forth at length in the following specification where I shall outline in full those forms of the invention which I have selected for illustration in the drawings accompanying and forming part of the present specification. In the drawings I have

shown several embodiments of my invention, but it is to be understood that I do not limit myself to these forms, since the invention, as expressed in the claims, may be embodied in other forms as well. 60

Referring to the drawings:

Figure 1 shows a system embodying my invention for relaying a telegraphic signal by aid of a 3-electrode tube; 65

Fig. 2 shows a modification of the system in which static or other disturbances are eliminated and in which increased power may be obtained due to the use of the energy of the compensating wave; and 70

Fig. 3 is a modification of the system shown in Fig. 2, in which a vibratory relay is utilized. 75

When signals are radiated at telegraphic speed over space and received in an antenna system 11, such as shown in Fig. 1, the received energy is usually extremely small. I utilize the received signal to cause actuation of an electro-magnetic relay 9 having an armature 14, so as to make and break contacts between conductor 17 and either of the conductors 15 and 16. These three conductors may lead to an appropriate recording device or to any other form of signal receiver, or may be used to conduct the signal 80 to a transmitting station to be transmitted. The relay 9 is in series with a source of direct current 10, such as a battery, and I make the variations in the current flow 85 through this battery large enough to enable the relay to attract and drop its armature 14. This effect I am able to secure by the use of a plurality of three-electrode rectifying tubes 18, 19, 20 and 21. These tubes are preferably of the audion type, and by connecting them as shown in Fig. 1, the direct current flowing through the battery 10 may 90 be made to vary by a large enough amount so as to operate the relay. By connecting the tubes as shown, the minute pulsations produced by the signal are caused to produce larger and larger pulsations in the plate circuits of the successive tubes. The effect of the signal current is immediately 95 felt on the relay, and it has been found possible to operate this relay at the speed necessary to take the incoming signals. The signaling current itself is caused to flow in a tuned circuit consisting of the coil 12 coupled to the antenna circuit, and the adjustable condenser 13. Any other well known 100 receiving circuit may, however, be used.

110

The importance of making the relay absolutely reliable can be better appreciated when it is realized that such relays form the connecting link in repeater systems; that is, systems in which a received signal is transmitted, for example, through conductors such as 15, 16 and 17 of Fig. 1 to a comparatively distant radio transmitting system and there again transmitted.

- 10 In systems where a compensating wave which transmits energy even while no signal is transmitted, is used, it is obviously an advantage to be able to use this compensating wave as well as the signaling wave for increasing the power of the signal. This increase in power, of course, is of great utility for relay systems, described hereinbefore. One form in which the compensating wave may be made to assist the signaling wave in the operation of a mechanical relay is shown in Fig. 2. In this figure I have not shown any amplifying means separate from the rectifying means, but it is to be understood, of course, that the signals may be properly magnified in case it is found desirable. The antenna circuit 11 is shown in this instance as inductively coupled to two systems labeled respectively T and C. These two systems are substantially similar, the system T being adapted to receive the telegraphic signals, and the system C being adapted to receive the compensating wave between signals. Since these two systems are similar, it will be sufficient to describe but one of them. The system T comprises a pair of 3-electrode tubes or audions 22-23 arranged to rectify both half waves of the received signal. For this purpose, there is interposed between the tubes 22 and 23 and the antenna circuit 11, a transformer 24, the primary of which consists of two coils in parallel. The secondary coils 25 and 26 are joined together at the point 27 and their free extremities are connected to the grid elements 28 and 29 of the tubes 22 and 23. The filaments 30 and 31 are adapted to be heated in any well known manner, not shown, and are connected together at the point 32. A battery 33 is connected between the points 27 and 32. It is thus seen that the input circuit of each tube 22 or 23 comprises the battery 33, one of the coils 25 or 26, a filament, and a grid. The plates 34 and 35 are likewise connected together and between the points 36 and 32 is connected the output circuit of the system T. This output circuit includes the battery 37 and the wires 38 and 39. It is believed that the operation of this system to rectify the signal is apparent. By properly tuning the receiver circuit system, as by manipulation of an inductively coupled coil 40 and the variable condenser 41, this system may be made sensitive to the telegraphic signals.
- 65 The system C has elements substantially

similar to the system T, its receiving elements consisting of the coil 42 and condenser 43 tuned to be sensitive to the compensating wave between signals. The wires 43 and 44 leading from system C correspond with the wires 38 and 39 of the system T.

A relay 45 is so connected to both of the systems T and C that while no signal is received, a pivoted armature 46 is held against the right hand pole piece 47 of the relay core. Upon the receipt of a signal this armature 46 is not only repelled from the pole 47, but it is attracted to the left hand pole 48. When the signal ceases, there is a repulsion between the left hand pole piece 48 and the armature 46 and it returns to its former position against the pole piece 47. To obtain this result the armature 46 is polarized; that is, it consists of either a permanent magnet or an electromagnet having its free end either a north or south pole. In the present instance, it is shown as a south pole. The output circuit of the compensating wave system C is connected in series with two coils 51 and 52 which are conveniently disposed on the opposite legs of the relay core, the direction of magnetization produced by these coils being, for example, that shown by the arrows 49 and 50. It is evident that while no signals are being received the coils 51 and 52 are energized from the system C and produce a north pole at 47 and a south pole at 48. The result, of course, is that the south pole of the pivoted armature 46 is attracted to the north pole 47 and connection is made between the wire 53 and the wire 54. As soon as a signal is received, however, the coils 51 and 52 become inactive and instead the coils 55 and 56 receive appreciable energy from the system T. The change from a substantially inactive state to an active one is controlled by the effect of signals on the grids 28 and 29 of the thermionic device 22 and 23. The provision of battery 33 assists in bringing the plate current substantially to zero when signaling ceases. An analogous condition exists for the system C, where the cessation of the compensating wave renders coils 51 and 52 substantially inactive.

Coils 55 and 56 are arranged, when they are active in response to the reception of a signal, to produce a magnetization in a direction opposite to that produced by the coils 51 and 52. The result is that poles 47 and 48 change their polarity, and the armature 46 swings to the left while this signal is being received and contact is made between wires 54 and 57. The systems T and C are so proportioned that the magnetizing effects of the coils 51 and 52 are substantially equal to the magnetizing effects of the coils 55 and 56. The energy received from the compensating waves in system C is useful in moving the armature 46 back to its

position when no signal is received. In this way, a stronger movement of armature 46 is obtained. Another great advantage of this system is that many interfering effects such as static or the like which are present both in the compensating waves and in the telegraphic waves, produce no effect whatsoever on the position of the armature 46, since the coils are differentially connected as regards these disturbances. While I have shown in this figure a scheme for rectifying both of the half waves of the signaling wave and the compensating wave, it is of course evident that it would be possible to use only one-half of the wave in each case.

The system shown in Fig. 2 may, however, be used equally as well when uni-wave signals are received; that is, when there is no compensating wave filling in the gaps between the signaling waves. Under such circumstances, the system C is tuned to be sensitive to a frequency only sufficiently different from the frequency of the signal waves that it cannot receive any appreciable signaling energy. The energy received by the system C would then depend upon the interfering waves, and since these interfering waves would have substantially the same effect on the systems T and C, they would be canceled out by the differential connections of coils 51, 52, and 55, 56. The armature 46 would not be affected in any way by these disturbances.

While it is possible as described in connection with Fig. 2 to increase the strength of the signal greatly by using a polarized relay, another arrangement is illustrated in Fig. 3, where the energy to operate the signaling relay is obtained from an external source. In this figure, a polarized relay 58 is shown, having the same general mechanical construction as that shown in Fig. 2. A movable polarized armature 59 is arranged so as to complete the circuit for the main relay 65, which controls the flow of current in conductors 74, 75 and 76, in the well known manner. The differential relay is provided with energizing coil C and T connected so as to act differentially upon the core of the relay 58, and to be supplied with energy respectively from systems such as C and T of Fig. 2. The core carries in addition, however, a pair of coils 61 and 62, which are so connected as to cause the armature 59 to vibrate between the poles of the core while neither of the sets of coils C or T are active. This is accomplished by the aid of the connections shown.

Assume for example that the armature 59 is in the right hand position, momentarily. The circuit for coil 62 includes the connection point 68, an armature 59, contact 64, right hand half of battery 63, relay coil 65, connection point 67 and adjustable condenser 79. While the condenser 79 is being

charged, a current flows in this circuit in a direction tending to produce magnetization in the direction of arrow 70. The result is that a north pole N is formed on the right hand pole piece 71 which attracts the pole S of the armature 59. A circuit is also completed for the coil 61, which circuit includes point 68, armature 59, contact 64, right hand half of battery 63, relay coil 65, point 67, and adjustable resistance 77. Due to the large self-induction of this circuit, however, the current does not rise to its full value until after the condenser 79 is fully charged, stopping current flow in coil 62. The magnetomotive force of coil 61 is in the direction shown by the arrow 69, and produces a north pole N on the left hand pole piece 78. Since at this stage the current through coil 62 is interrupted by the fully charged condenser 79, there is no longer any pole formed on the right hand pole piece 71, and the result is that the left hand pole piece 78 is free to attract the armature 59 and interrupt the circuit for both coils. As soon as this occurs, the condenser 79, having no impressed counter E. M. F., discharges through coil 61 and resistance 77, producing a current flow in the same direction as before in the coil 61, but in the reverse direction in coil 62, as shown by the dotted arrow 80. This produces a south pole at the right hand pole tip 71, which assists in repelling the armature 59 to the left, while at the same time a north pole is formed at the left hand pole piece 78 which urges the armature 59 likewise to the left. However, as soon as the extreme left hand position of armature 59 is reached as indicated by the dotted line 72, the current flow is reversed in the coil 61, and a magnetomotive force is gradually built up through resistance 77 in the direction shown by the dotted line arrow 81. This produces a south pole at the left hand pole tip 78, tending to repel the armature 59. At the same time the condenser 79 has been rapidly charged in a reverse direction; and during the charging period a magnetomotive force in the direction of dotted arrow 80 is produced, tending to keep armature 59 to the left. However, before the current through coil 61 builds up entirely, the condenser becomes fully charged and the current flow through coil 62 is interrupted. When this occurs, armature 59 is repelled to the right, and the circuit at contact 73 is interrupted. The condenser 79 can again discharge through coils 61 and 62, and the discharging current is in such a direction as to cause the armature 59 to be moved toward the right. When contact at 64 is again completed, the cycle of operations is repeated.

It is evident that by a proper choice of the capacity at 79 and the resistance at 77, the period of vibration of armature 59 may

be easily controlled. Furthermore, the circuit through relay coil 65 is made and broken once for each oscillation, and the alternate making and breaking would continue indefinitely.

The coils C and T, connected to the receiving antenna system, control the vibration of the armature. Thus, while coils T are active, a south pole is formed at the right hand pole piece 71 and a north pole at the left hand pole piece. The magnetomotive force of these coils is made large enough to overcome the magnetomotive forces of coils 61 and 62. The result is that the armature 59 is repelled from the pole piece 71 and attracted to the pole piece 78, and it is held in this position while the coils T are active. Similar effects are produced when coils C are active, except that in this case the armature is caused to be attracted to the right hand pole piece 71 and to remain there while these coils remain active.

The period of vibration of the armature may be made about equal to the period of the telegraphic signals when dots are received. In this way the telegraphic signals for dots may be very weak, as the local source of energy supplies the required power for moving the armature. This is especially useful where the coils C are energized not by a compensation wave but rather from a system slightly detuned from the frequency of the signal waves. In this way the effect of disturbing influences on the movement of armature 59, such as those due to static, may also be eliminated.

While the systems shown are adapted to operate on radio frequency current, it is of course possible by proper design of the receiving apparatus, to utilize energy at audio frequency produced by the beat note effect.

I claim:

1. In a system for receiving signals and relaying signals at telegraphic speed, a receiving circuit, an electronic device having an electron emitting electrode, a control electrode and an anode, means for connecting the receiving circuit to the electron emitting electrode and control electrode, an electro-magnetic relay including an armature and means connected between the relay and electronic device whereby the armature is actuated by the signals and means for imparting oscillatory movement to the armature whereby the latter is sensitized.

2. In a radio system for receiving and relaying signals at telegraphic speed, an absorbing circuit, an electronic device having an electron emitting electrode, a control electrode and an anode, means whereby the control electrode is affected by signals received in the absorbing circuit, an electro-magnetic relay, an operating circuit for the relay connected to the electronic device, and means for causing the operating circuit to

be active only during the reception of signaling impulses and means for energizing the relay between signaling impulses.

3. In a radio receiving system, an absorbing circuit, a circuit coupled to the absorbing circuit and arranged to be sensitive to waves of signaling frequency, a second circuit arranged to be supplied with energy from the absorbing circuit, a coil for each of the two latter circuits, means for opposing the magnetomotive forces produced by the two coils, an armature operated in accordance with the resultant magnetomotive force, and contacts controlled by the armature.

4. In a radio receiving system, an absorbing circuit, a circuit coupled to the absorbing circuit and arranged to be sensitive to waves of signaling frequency, a second circuit arranged to be supplied with energy from the absorbing circuit, and an electromagnetic relay having a movable armature, the two latter circuits being arranged to assist in the operation of the relay to move the armature in both directions.

5. In a radio receiving system, a relay having a polarized armature, and means for differentially energizing the relay in accordance with the signals and in accordance with substantially all the non-signaling energy received by the system.

6. In a radio telegraph receiving system, operating in such manner that compensating waves are transmitting between signaling impulses, means for rectifying the energy received during signaling, means for rectifying the compensating wave energy, and an electromagnet having a polarized armature energized differentially from both means.

7. In a radio signaling system, an absorbing circuit, a circuit adapted to receive the signaling energy, a circuit adapted to receive substantially all of the energy received by the absorbing circuit between signals, and a relay having an armature utilizing both these forms of energy for moving the armature.

8. In a radio signaling system, an absorbing circuit, a circuit adapted to receive the signaling energy, a circuit adapted to receive substantially all of the non-signaling energy received by the absorbing circuit, and magnetic means including a polarized armature energized differentially from both circuits whereby the signaling energy and non-signaling energy are opposed.

9. In a radio signaling system, a tube circuit arranged to rectify the current due to signaling, a tube circuit arranged to rectify the current due to substantially all of the non-signaling energy received by the system, and magnetic means for opposing the effects of the two currents.

10. In a radio signaling system, a tube cir-

cuit arranged to rectify the current due to the received signal waves, a tube circuit arranged to rectify the current due to substantially all of the non-signaling energy received by the system, and a relay differentially wound in accordance with the rectified currents.

11. In a radio signaling system, a tube circuit arranged to rectify the current due to the received signal waves, a tube circuit arranged to rectify the current due to substantially all of the non-signaling energy received by the system, and a relay having a polarized armature differentially wound in accordance with the rectified currents.

12. In a radio signaling system, a relay having an armature, local means for causing the armature to oscillate continuously between two positions, and a receiving circuit controlling the operation of said means.

13. In a radio signaling system, a relay having an armature, means for causing the armature to oscillate continuously between two positions, a circuit energized in accordance with the received signals, a circuit energized in accordance with the energy received between signals, and coils wound differentially on the relay energized respectively from the two circuits.

14. In a radio signaling system, a relay having a polarized armature, means for energizing the relay differentially with respect to the energy received during signaling and between signals, and means tending to cause continuous oscillation of the armature.

15. In a radio signaling system, a tube circuit arranged to rectify the current due to the received signal waves, a tube circuit arranged to rectify current due to energy re-

ceived between signals, a relay having an armature, means tending to cause continuous oscillation of the armature and coils differentially wound on the relay energized respectively from the two rectifying circuits.

16. In a radio receiving system, a relay comprising an armature, contacts controlled by the armature, and means for differentially energizing the relay in accordance with different wave length energy received by the system, whereby static or any other impulse interference may be eliminated.

17. In a radio receiving system, a relay comprising an armature, contacts controlled by the armature, and means for differentially energizing the relay in accordance with signaling energy and with energy from a wave frequency in the vicinity of the signaling energy wave frequency, whereby static or other impulse interferences may be eliminated.

18. In a radio receiving system, a pair of electronic devices each having a control electrode, an electron emitting electrode and an anode, means whereby one of the control electrodes is affected by the reception of signals, means whereby substantially all of the non-signaling energy received by the system affects the other control electrode, a relay having differential coils connected respectively to the two thermionic devices, and means whereby the reception of signals changes that coil of the relay which is connected to the signal responsive electronic device from an inactive to an active state.

In testimony whereof, I have hereunto set my hand.

WALTER N. FANNING.
